MINIATURE ANIMAL TOY CAR

Jack N. O'Connor and Stella M. O'Connor,
Los Angeles, Calif.

Application July 16, 1945 Serial No. 605,296

2 Claims. (Cl. 280—1.13)

1

Our invention relates to improvements in a miniature animal toy car or child's vehicle, the primary object being to provide improved means by which an appealing device of its kind is produced and the child is furnished with a strong and durable article of its kind which can be easily propelled and steered without danger of upsetting. Among further objects is maximum simplicity of construction and increased effectiveness in use.

In the accompanying drawing, forming part of this specification, Fig. 1 is a perspective view of our improved miniature animal toy car or child's vehicle; Fig. 2 is a vertical section taken substantially on the line 2—2 of Fig. 1; Fig. 3 is a vertical section taken on the line indicated by 3—3 of Fig. 1; Fig. 4 is a perspective view, partly diagrammatic, of a detail, illustrating the steering head and its cooperating swivel; and Fig. 5 is a vertical section of a detail showing a portion of the swivel and of the hand-operable steering head applied to the platform of the vehicle.

In the drawing, A is a horizontally disposed platform, which has a broad back seat portion 10, a forward disk-like bearing member 11 and a longitudinal connecting neck portion 12 between said seat and bearing. This structure enables a child to assume sitting posture while facing forwardly on the seat with his or her legs straddling the neck and with his or her arms within easy reach of the bearing portion of the platform.

The seat portion of the platform is secured to a transverse bolster 13, the upright side arms 14 of which are journaled upon the opposite end portions of a horizontal transverse shaft 15. Carrier wheels 16 and 17 are rigidly secured to the ends of or may be journaled on said shaft. The bolster and platform are braced and reinforced by a longitudinal rib 18, which is rigidly secured to the bolster and extends forwardly below and is rigidly secured along the seat and neck portions of the platform.

The forward bearing portion 11 of the platform is pivotally mounted and journaled upon a centrally and vertically disposed shaft 20, which has an annular bearing shoulder 21 engaged below the bearing member 11 and an upwardly extended stub shaft portion 22 which projects above and is journaled through the bearing 11. The swivel shaft 20 also has a downwardly extended squared vertical end portion 23 upon the lower end of which a horizontal crank shaft 24 is journaled by the bearing 25. Carrier wheels 55

2

26 and 27 are rigidly secured to the outer projecting horizontal end portions of shaft 24 and said end portions are formed with integral crank arms 28 and 29 to which foot pedals 30 are freely journaled to enable the occupant to propel the vehicle.

A steering head 31, composed of a vertical plate, the marginal edge of which is shaped to resemble the head portion of an animal such as a horse 10 or other object is rigidly secured to the upwardly extended portion of the stub shaft 22 in normally longitudinal direction. The lower edge 32 of the head plate 31 bears rotatively on the surface of the bearing plate 11 and completes the swivel journal connection between the forward wheel mount and the platform. The steering shaft is joined to the steering head plate by a slip joint 33 as shown in Fig. 4.

A laterally extending handle bar 34 is secured 20 through the steering head plate, which the occupant may grasp for directing the front carrier wheels. In addition to the fanciful shape of the steering head, the rear end of the platform may be decorated with a tail piece 35 to assist in imparting the fanciful representation of an animal to the entire device. Also breast and hip guards 36 and 37 are secured to and extended downwardly from the marginal edges respectively of the front bearing plate and the seat portions 11 and 10. The lower edges of these guards are scolloped 30 to assist in imparting respectively the representation of the breast portion and hip portion of the animal of which the device is designed to simulate.

Plates which are shaped marginally to represent the back legs 40—40 of an animal such as a horse are pivotally hung at 41 (Fig. 3) from depending supports 42 on the opposite sides of the seat above the shaft 15. The lower feet ends of these legs are respectively connected to the 40 wheels 16 and 17 by a crank pin 43 and a cooperating slotted cleat 44 which is disposed longitudinally on the inner side of the adjacent leg member. By this means the back legs are reciprocated on their pivot supports 41 so as to simulate motion as the vehicle is propelled forwardly or backwardly. The front end portion of the vehicle is also provided with a pair of plates representing the front legs 45—45 of an animal such as a horse. These front legs are hung from lateral supports 46 (Fig. 2) on the opposite sides of the squared portion of the swivel body 23 and are journaled by their lower ends on the crank shaft 24.

In use the occupant of the vehicle can propel the vehicle by foot power applied either to the foot

pedals 30 or directly to the surface of the ground upon which the vehicle is used. The occupant can also simultaneously steer and guide the vehicle by the handle bar 34 or directly by the steering head. While seated on the platform the occupant is braced by the curved back 48 which is secured rigidly on the seat portion. The hip and breast plates in addition to representing portions of the body of an animal shield portions of the legs and their working connections with the platform and swivel shaft from view.

Modifications are contemplated within the spirit of the invention and within the scope of the following claims:

We claim:

1. A child's vehicle, comprising a flat platform having a back seat portion, a forward disk-like bearing portion and a connecting neck portion between said seat and bearing, a transverse bolster secured below the seat, carrier wheels journaled upon said bolster, a vertical swivel body having a stub shaft journaled upwardly through said bearing, a vertical steering head plate mounted upon said shaft and revolvable by its lower edge upon said bearing, a crank shaft journaled on the lower portion of said swivel body having crank arm members, carrier wheels journaled on said shaft, foot engaging pedals mounted on the crank arm members of said crank shaft, back leg plates pivotally hung from the back seat portion of said platform and having crank pin connections with the back carrier wheels to impart reciprocal motion thereto as the wheels revolve, front leg plates having their upper end portions secured to the swivel body and journaled by their lower end portions on said crank shaft whereby said leg plates are caused to swing with the rotation of said swivel body, a hip guard plate depending from and secured to the marginal edge portion of the platform and shielding a portion of the back legs from view, and a neck guard plate depending from and secured to the bearing portion of the platform and shielding a portion of the front legs from view.

45

2. A child's vehicle, comprising a platform having a broad rear seat portion, a forward horizontal bearing plate and a connecting neck between said seat and bearing plate, a carrier swiveled upon said bearing plate and having a steering head plate above said bearing plate, rear carrier wheels journaled below and supporting the seat rear portion of the platform, a rear leg pivotally supported below the seat rear portion of the platform outwardly beyond each of said rear wheels, a pin and slot connection between the inner face of the free end portion of each rear leg and its companion wheel by which reciprocal motion is imparted to the rear leg by the revolution of its connected wheel, and a shield depending from the outer edge of said platform in front of the pivot connections between said rear legs and platform.
